UNITED STATES PATENT OFFICE.

JOHN H. ROSE, OF HOLYOKE, MASSACHUSETTS.

ELEVATING-TRUCK.

1,325,863.

Specification of Letters Patent. Patented Dec. 23, 1919.

Application filed May 7, 1919. Serial No. 295,331.

To all whom it may concern:

Be it known that I, JOHN H. ROSE, a citizen of the United States of America, residing at Holyoke, in the county of Hampden 5 and Commonwealth of Massachusetts, have invented certain new and useful Improvements in Elevating-Trucks, of which the following is a specification.

This invention relates to improvements 10 in trucks of the type known in the trade as elevating trucks. An object of the invention is to provide a truck which can be easily operated when the load is raised, and one that is so constructed that it can be automatically locked in its elevated position, 15 and readily released or unlocked when the load is to be lowered.

In this class of trucks a main supporting frame is supported on wheels to permit its 20 ready transportation along the floor, a second frame is pivotally connected to the main frame for vertical movements in relation to the main frame, operating mechanisms are associated with the handle for 25 raising and lowering the second frame and means for automatically locking the second frame in its elevated position.

In use, the truck, when the second or upper frame is lowered, is pushed under 30 "skids" on which the load to be raised is placed, the second frame is then elevated to raise the load on the skids, the load is then transferred to another point or part of the room as desired, at which point the 35 second or upper frame with its load is lowered and the truck again used to haul another load.

A feature of my present invention relates 40 to the construction of the swivel head to which the operating handle is attached. Other objects and features of my invention will be apparent from the following description, and particularly pointed out in the claims.

45 Referring to the drawings:

Figure 1 is a side elevational view, partly in section, on the line 1—1 of Fig. 5, showing the lifting, locking and unlocking mechanism and with the elevating frame lowered. 50 Fig. 2 is a view similar to Fig. 1, but showing the elevating frame raised and locked and with the handle released from the elevating connecting devices.

Fig. 3 is a vertical sectional view on the

line 3—3 of Fig. 2 showing the construction 55 of the swiveled head and front supporting rollers.

Fig. 4 is a vertical sectional view on the line 4—4 of Fig. 3.

Fig. 5 is a plan view of the complete 60 truck with the elevating frame lowered and Fig. 6 is a side elevational view of Fig. 5.

Referring to the drawings in detail; the main supporting frame is indicated as a whole by the numeral 1 and the elevating 65 frame as a whole by the numeral 2, rear supporting wheels are indicated at 3 and 4, which are secured to the axle rod 5 in the frame 1, front supporting wheels are indicated at 6 and 7, which are supported in the 70 swivel truck frame 8 that turns in a yoke-shaped piece 9 that spans the distance between the front ends of the lower frame, the downwardly extending ends of which are secured to the front ends of the side bars 75 10 and 11 of the main frame, as indicated at 12 and 13. The upper surface of this yoke-shaped piece is provided with a rib or flange 14 having ears 15 between which the foot lever 16 which releases the locking 80 latch is pivoted. Depending from the upper part of the yoke 8 are parallel projections 17, and extending from one to the other and secured thereto is a pin 18. Piv- 85 tally mounted on this pin for swinging movements laterally of the truck is a block 19 having a depending piece 20 in which is supported the axle rod 21 on the outer ends of which are secured the wheels 6 and 7 of the truck. The upper part of the yoke 90 member 8 has an upwardly projecting circular part 22 which serves as a pivotal pin and connecting means between the yoke member 9 and the truck 8, whereby the truck 8 with the wheels 6 and 7, can revolve 95 completely around in the yoke shaped member 9. It will also be observed that the wheels 6 and 7 and the block 19 can turn in a vertical plane on the pin 18, as shown in Fig. 3, where the wheels 6 and 7 are in- 100

105 indicated as passing over an obstruction indicated by the dotted line 23, or in other words, the wheels of the forward end of the truck are so mounted as to have substantially a universal joint movement.

Referring to the means for operating the upper or elevating frame 2, this frame is connected to the frame 1 by means of the

upper and lower links 24 and 25, which are located at the forward end of the frame 2 and the links 26 and 27, which are located at the rear end of the frames 1 and 2. 5 These links are of the same length and are pivoted together at their inner ends, as shown by the rod 28. The upper ends of the links 24 are formed integral with the rod or part 24' which is pivotally mounted 10 in the side bars of the frame 2. The lower ends of the links 25 are formed integral with the rod or part 25' which is pivotally mounted in the side bars of the lower frame 1. The links 26 are cast with the rod 26' 15 which is pivotally mounted in the rear end portions of the side bars of the frame 2, and the links 27 are cast with the rod 27' which is pivotally mounted in the side bars of the lower frame 1. The rods which connect 20 the inner ends of the links 24 and 25 and 26 and 27 are also connected together for simultaneous operation by means of the bar 37 which will be described. The links constitute what may be termed 25 knuckle-joint structures between the frames 1 and 2.

29 designates oppositely disposed links which are pivotally attached at their upper ends to the frame 2 and at their lower ends 30 to the frame 1. These links serve to maintain the parallelism between the two frames during their upward and downward movements and also to cause the upper or elevating frame 2 to move vertically into its extreme upward position (as otherwise the links 24, 25, 26 and 27 would turn independently of each other, which would permit the frame 2 to fall down onto the frame 1. 30 designates the lever or handle by means of 35 which the truck is drawn along the floor and also by means of which the frame 2 is elevated. This handle is pivoted to the pivot or swivel part 22 of the truck frame 8 as indicated at 31. It is formed with a notch 40 or recess 32 in its forward edge. 33 is a U-shaped ring-like member that passes around the lever 30 and is formed with a forwardly extending portion 34. Attached by means of the pin 36 to the inwardly 45 extending ends 33' of the member 33 is a link 35. This link is pivotally connected to the link 36', which in turn is pivotally connected to the bar 37 at the pivotal point 38. This bar extends rearwardly of the 50 machine and is connected to the rods 28 and 39. Also attached to the rod 28 is a latch 41 having a downwardly extending portion 42 and an inclined forward edge part 43. Between the portions 42 and 43 is a recess 60 44. The locking latch 41 is connected at its forward end to a link 45, which in turn is connected to the foot piece 16. 46 is a fixed bar passing transversely of the frame 1 and rigidly secured thereto and with 65 which the recess 44 of the latch 41 engages

when the elevating frame 2 is in its raised position. The part 42 is a stop-dog to prevent the frame 2 from going beyond the vertical or elevated position, or in other words it acts as a stop. 70

Considering the parts in the position shown in Fig. 6 and also assuming that a load is placed on the elevating frame 2, the operator, by means of the extension 34 first raises the ring like member 33 into engagement with the recess 32 of the handle. He then pulls the handle forward in the direction of the arrow indicated at 47. As this lever is moved forward the links 33, 35, 36' and bar 37 pull on the bars 28 and 39, causing the links 24, 25, 26 and 27 to assume the nearly vertical position shown in Fig. 2. As the frame 2 rises and moves forward, the latch 41 by reason of the inclined edge 43 slides over the locking bar 46 until the 85 recess 44 engages the same. This latch holds the frame 2 elevated as readily understood. The operator then moves the handle lever 30 rearward allowing the ring 33 to fall into the position shown in Fig. 2. 90 The swivel truck 8 in which the wheels 6 and 7 are mounted, is now free to be turned in any direction for drawing the loaded truck about the room. When it is desired to lower the frame 2, the operator presses 95 downward on the forward part 16' of the lever 16, whereby the latch link 41 is raised and unlatched from the bar 46 permitting the frame 2 to go back by gravity. In order to prevent the frame 2 from descending too 100 rapidly, a cushion device is provided which comprises a cylinder 48 shown in Fig. 5, which is preferably filled with oil and against which a piston therein operates and which is connected by means of the rod 49 105 to the rod 28. When the frame 2 reaches the position shown in Fig. 6, the parts are then ready to receive and unload and the same operations are repeated. 110

In order to prevent the wheels 3 and 4 from being injured plates 50 with inclined edges 51 are provided. Also attached to the ends of the frame 2 is a plate 52 having inclined edges 53. 115

From this construction it will be seen that the double link connection between the frames 1 and 2 has the effect as the links 24, 25, 26 and 27 straighten out of materially increasing the leverage. 120

It should be particularly observed that by reason of the swivel structure shown at the forward end of the truck that the apparatus is always in alignment, or in other words in case of any unevenness of the floor or other support, all of the wheels will have a bearing as indicated in dotted lines in Fig. 3, where the truck wheels 6 are tipped and in engagement with the obstruction 23. Or in other words the truck as a whole will be maintained in a position that is substantially 125 130

parallel with the supporting surface and independent of any great unevenness of the floor.

It will also be observed that the operating handle is only connected to the lifting platform during the lifting operations. At all other times it is free to turn the forward truck member in any direction for steering and guiding the truck as a whole. By employing the knuckle-joint structure for connecting the frames and which comprises two rigid U-shaped members, as shown in Fig. 5, the integral arms 24 and 25 of which are connected together by means of the common pins 28 and 39 and the draw bar 37 which is connected to these pins the elevating frame 2 will be raised and lowered uniformly over its whole surface. That is to say, there will be no swaying or sidewise movement. In addition the links 29 are used to constantly maintain the parallelism between the frames to prevent one end from accidentally dropping down.

It will be observed that the knuckle-joint arms 24, 25, 26 and 27 of the knuckle-joint structure provide increased leverage since the bar 37 is connected to the rods 28 and 39, thus producing a double leverage effect on each pair of knuckle joint structures. That is to say, the leverage arms extend from the centers of the rods or portions 24' and 25' to the line of draft passing through the median line of the bar 37 from the rods 28 and 29. The same double arm leverage effect is present from the centers of the rods 26' and 27' to the bar 37.

What I claim is:

1. In an elevating truck, a main frame, an operating handle, wheels for supporting the main frame, an elevating frame, knuckle-joint structures for pivotally connecting the two frames, a rod connecting said knuckle-joint structures, and means for operating the elevating frame from the handle, including a member for engaging the handle, and link connections between the said handle engaging member and the elevating frame, means for retaining the elevating frame in an elevated position including a hook extending forward of the knuckle-joint structure connecting rod, and which is operated by the elevating frame, and which automatically engages a part on the main frame when the elevating frame is in its uppermost position to prevent the elevating frame from moving beyond its elevated position.

2. A truck for the purpose described, comprising a main frame, a handle connected thereto, an elevating frame, knuckle-joints for supporting the elevating frame and connected to the main frame, means including a member engaging the handle for operating the elevating frame from the handle, means including a hook for retain-

ing the elevating frame in its elevated position, means for unlocking or releasing the elevating frame comprising a lever designed to be operated by the foot of the operator, and connecting means between the lever and the hook.

3. In a truck, a main frame and an elevating frame, means for maintaining a parallel position of the frames comprising knuckle-joint structures pivotally attached to said frames, a handle bar, connecting means between the handle-bar and the said joint structures, comprising a member adapted to temporarily engage the handle bar, connecting means between the pivotal points of said joint structures, means including a hook having a stop-dog part for preventing said elevating frame from moving beyond its raised position and for retaining the elevating frame in said position, and means for releasing said frame, as described.

4. In an elevating truck, a main supporting frame, wheels at the forward and rear ends of the same, an elevating frame, knuckle-joint structures for connecting the frames together, a handle, connecting means between the handle and the elevating frame, means for locking the elevating frame in its elevated position comprising a hook member connected to and movable with the elevating frame and having a recess and stop-dog portion to engage a rod on the main frame, and a lock releasing lever on a part of the main frame and connected to the locking means, said lever being designed to be operated by the foot of the operator, as described.

5. In an elevating truck, a main frame, a swivel wheeled truck structure for supporting the forward end of the main frame, a yoke connecting the forward ends of the main frame, and in which the forward swivel wheeled truck operates, an operating handle connected to the swivel wheels, an elevating frame mounted on the main frame and connected to said handle, transversely located rods in the frames, knuckle-joint structures connected to the rods and to each other, connecting means between the rods and the operating handle for raising the elevating frame, said connecting means being so constructed to have engagement with the operating handle only during the elevating operations and to be free from such engagements during the time the truck is drawn along the floor.

6. In an elevating truck, the combination, of a main frame and an elevating frame, means for connecting the frames together comprising knuckle-joint structures, means for constantly maintaining the parallelism of the frames, stop means for limiting the upward movement of the elevating frame, an operating handle, and means for connect-

42
ing the handle and elevating frame only during the elevating operations, but leaving the handle free at other times.

7. In an elevating truck, the combination, 5 of a main frame, an elevating frame, means comprising knuckle-joint structures for connecting said frames, an operating handle, connecting means between the handle and the elevating frame, said means including a 10 horse-shoe shaped member between the handle and the frame for engaging the operating handle only during the elevating operations.

8. In an elevating truck, the combination, 15 of a main wheel-supported frame, a frame movable toward and away from said frame, knuckle-joint structures connecting the frames, a bar connecting the knuckle-joint structures, an operating handle, connecting 20 means between the movable frame and the handle, and a link connecting the frames for maintaining constant parallelism between the frames during the movements of the movable frame.

25 9. In an elevating truck, the combination, of a main wheel supported frame, an elevating frame, knuckle-joint structures piv-

otally connecting the frames, an operating and steering handle, connecting means between the handle and the elevating frame, 30 means for automatically locking the elevating frame in its elevated position and to prevent the same from passing beyond its uppermost position and comprising a link, a recessed portion therein for engaging a 35 fixed rod on the wheel supported frame, means for disengaging the locking link including a lever connected to said link, and designed to be operated by the foot of the operator.

10. In an elevating truck, the combination, of a main frame, an elevating frame, knuckle joint structures for pivotally connecting the frames and for maintaining a rigid and supporting device at the upper 45 corners of the elevating frame, pins connecting the arms of the said joint structures, a draw bar connecting the pins, and operating handle, and connecting means between the bar and the handle, whereby the elevating frame will be raised and lowered and constantly maintained in a plane that is parallel to the main frame, as described.

JOHN H. ROSE.
